(57) **CLAIM**

The design for an aerial toy, as shown and described.

DESCRIPTION

FIG. 1 is a perspective view from above, to the front and to the left side of a new design for an aerial toy;

FIG. 2 is a perspective view from above, to the rear and to the left side thereof;

FIG. 3 is a perspective view from below, to the front, and to the left side thereof;

FIG. 4 is a perspective view from below, to the rear, and to the left side thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a front elevation view thereof; and,

FIG. 10 is a rear elevation view thereof.

In the drawings, the claimed design is defined by the shaded surfaces; broken lines immediately adjacent shaded surfaces represent boundaries of the claim and form no part thereof; all other broken lines depict portions of the aerial toy that form no part of the claim.

1 Claim, 9 Drawing Sheets
